FOREIGN PATENT DOCUMENTS

U.S. Appl. No. 29/295,291, filed Sep. 25, 2007, Tano, et al.

(57) **CLAIM**

The ornamental design for a polishing pad, as shown and described.

DESCRIPTION

FIG. 1 is a top plan view of a polishing pad showing our new design;

FIG. 2 is a front elevational view thereof, the rear elevational view, left side and front side elevational views thereof being mirror images of the views shown;

FIG. 3 is a bottom plan view thereof;

FIG. 4 is a partially enlarged view of portion 4—4 in FIG. 1;

FIG. 5 is a partially enlarged sectional view taken substantially along line 5—5 in FIG. 4;

FIG. 6 is a partially enlarged sectional view taken substantially along line 6—6 in FIG. 4;

FIG. 7 is a partially enlarged drawing of portion 7—7 in FIG. 3;

FIG. 8 is a partially enlarged sectional view of portion 8 in FIG. 5; and,

FIG. 9 is a partially enlarged view of section 9—9 in FIG. 1.
